UNITED STATES PATENT OFFICE.

GUSTAF LINDBERG, OF WALLA WALLA, WASHINGTON.

LAST.

1,325,023.

Specification of Letters Patent. Patented Dec. 16, 1919.

Application filed August 22, 1918. Serial No. 250,917.

To all whom it may concern:

Be it known that I, GUSTAF LINDBERG, a citizen of the United States, residing at Walla Walla, in the county of Walla Walla 5 and State of Washington, have invented certain new and useful Improvements in Lasts, of which the following is a specification.

This invention relates to lasts used in the 10 repair of shoes having high heel and pointed toes, and has for its object the production of a last whose curves are such as will conveniently reach any part of the shoe for which it is intended, and whose sharp edges will 15 reach the farthermost corners thereof.

This invention further consists of certain 20 novel features which will be fully understood by reference to the description of the drawings and to the claim hereinafter given.

Referring specifically to the drawings—
Figure 1 is a side elevation of the last;
Fig. 2 is a plan view from below; and
Fig. 3 is a section on the line 3—3 of

Fig. 1.
25 In the drawings like numerals refer to like parts and 1 is the sole proper having a heel portion 2, a shank portion 3, and a toe portion 4. The heel and shank portions, 2 and 3 respectively, of the sole have convex 30 surfaces 5 while the toe portion 4 is a flat plane.

By referring to Fig. 1 it will be noted that the curves shown in the dotted line 6, which represents the shape of the present 35 high heel shoe, do not parallel the curved edges 7 of the last; the convex portion of the reverse curve, constituting the curve of the last, being of greater curvature than that of the shoe, and the concave portion being 40 of less curvature than that of the shoe enables the last to be placed in close contact with any part of the sole of the shoe at will.

This last is a solid block of metal and is used with a stand, (not shown) and is recessed at 8 to engage the stand in the usual manner.

The underside 9 of the last is concaved to form a sharp peripheral edge 7 about the sole and extends from the heel all the way 50 around to the toe forming a uniformly sharp edge to the last.

By referring to Fig. 2 it will be noted that

the curves shown in the dotted lines 10, which represents a composite shape of the present pointed toed shoe, does not parallel 55 the curves of the peripheral edges of the last, and in this the convex portion of the reverse curve is of greater curvature than the corresponding curvature of the shoe, while the concave portion is of less curva- 60 ture than the corresponding curvature of the shoe; thus the last may be brought into contact with all corners of the shoe formed by the junction of the sole and upper, at will. 65

The use of the last is well known and does not require description but the great fault of lasts, that of reaching all parts of the sole of the high heeled and pointed toed shoe of the present day effectually, is overcome by this last as by its curved surfaces and the design of the curves of the peripheral edge of the sole it will reach that part of the shoe, readily and effectually, for which it is intended. 70 75

Having thus described my invention, I claim—

A last composed of substantially a solid block, having a longitudinally curved sole 80 consisting of reverse curves, the concave portion of which has less curvature than the corresponding curves of a shoe, and the convex portion of which has greater curvature than the corresponding curve of the shoe, and whose heel and shank portion is a laterally convexed surface, and whose toe portion is a flat plane, having concaved undersides extending from the heel all the way around to the toe, and having sharp peripheral edges curved about the sole, said edges 85 consisting of reverse curves, the concave portions of which curves having less curvature than the corresponding curves of the shoe and the convex portions of which curves having greater curvature than the 90 corresponding curves of the shoe, and said edges being formed by the concaved undersides. 95

In testimony whereof I affix my signature.

GUSTAF LINDBERG.
